UNITED STATES PATENT OFFICE.

GEORGE M. BRADT, OF CHATTANOOGA, TENNESSEE.

SELF-REGISTERING CHECK-PUNCH.

SPECIFICATION forming part of Letters Patent No. 642,955, dated February 6, 1900.

Application filed May 23, 1899. Serial No. 717,915. (No model.)

To all whom it may concern:

Be it known that I, GEORGE M. BRADT, a citizen of the United States, residing at Chattanooga, in the county of Hamilton and State of Tennessee, have invented certain new and useful Improvements in Self-Registering Check-Punches; and I do hereby declare the following to be a full, clear, and exact description of the invention, such as will enable others skilled in the art to which it appertains to make and use the same.

This invention relates to an improvement in self-registering punches of the kind used in commissary stores—such, for instance, as those carried on by furnace or mining companies where the employees have their wages paid in orders on the store.

The object is to provide a simple mechanism by which the amount of each purchase may be punched from a card, while at the same time the registering mechanism arranged in connection with the punching device will automatically record the amount punched out each time.

In the annexed drawings, illustrating my invention, Figure 1 is a vertical sectional view of my improved store check-punch. Fig. 2 is a top plan view of the same. Fig. 3 is a partial front elevation. Fig. 4 is an enlarged front view of the slide-plate and adjacent parts in partial section on line $x-x$ of Fig. 5. Fig. 5 is a sectional detail view.

Like letters of reference denote like parts in all the figures.

The present invention is an improvement upon that set forth in the Letters Patent granted to me on January 19, 1897, No. 575,616, as the assignee of Carl T. Painter, for a self-registering check-punch.

A denotes the main casting or supporting bed or frame of my improved check-punch, said casting being mounted upon the card-receiving box C, having a door C'. The front part of casting A is recessed at A², and below this recess is a vertical passage a', which leads down into the box C and through which the punching-die operates. A card may be placed in the casting and above opening a' for the purpose of being punched. Adjacent to opening a' is a guide a, secured in place by a screw or other means and being of a spring character, so that it may act to hold

the card in place while it is being punched. The part A' of the bed or frame which is directly above opening a' is formed with a vertical bore or passage to receive the vertically-movable punching-rod D, that carries the punch or die d, which operates upon the card and punches out therefrom the desired numeral or numerals, the punched-out parts dropping down through the passage a' into the box C. The rod D is provided with a horizontally-projecting lug D', under which is a spiral spring D², which acts to normally lift the rod D, said spring D² being held in a recess in the upper part of that portion of the frame designated A'. Said bored part A' of the frame is provided above with ears or lugs A³ A³, in which is pivoted a cam-shaped casting E, that operates from the upper end of the vertical rod D. The forward part of casting E is formed with a flat bar E', having stops e e at each end, and on this bar E' is designed to rest and be capable of sliding between the stops e e a pivoted angular bar F, the rear end of which is pivoted by a pivot-pin f to the bearing projection E² on the rear side of casting E, while the front part of bar F has a horizontal forwardly-projecting pin F² and above that a handle F', whereby the cam can be operated and the handle-bar F oscillated sidewise between the stops e e.

The front part of casting A is chambered to receive a block G, which rests on leveling-screws g g and is secured in place by means of the securing or clamping screw O. This block is rabbeted on the upper side, and in this rabbet is arranged to reciprocate a sliding plate K, having inclined slots k, k', and k² cut therein and provided with a horizontal end-projecting pin K², against which acts a spiral spring located in a recess in the thickened bottom part of slide K, as shown in Figs. 4 and 5, and which normally presses the pin K² outward against the inner end of the chamber in frame A. At this same end of plate K the latter has a rectangular notch K' made therein to accommodate the position of pin K² and the endwise movement of the plate. Pivoted to the plate K is a ratchet-bar L, the teeth of which are normally kept in engagement with a toothed wheel M by means of the flat spring l. When the plate K is reciprocated toward the right, (see Fig. 4,) the result

is to rotate the wheel M to a greater or less extent, varying according to the distance which the plate K moves in its reciprocation. Wheel M actuates a train of wheels belonging to any suitable registering mechanism. This mechanism may be of the kind shown and described in my former patent, hereinabove alluded to, or any other acceptable form, and it is therefore unnecessary to further describe the details thereof here.

On the rear side of sliding plate K is a stationary slotted plate H, that is secured to the block G by means of screws h, and on the front side of plate K is another slotted plate I, that is suitably held in place. The slots i in plate I are directly opposite to and of similar shape to the slots in plate H. The sliding plate K moves easily between the two plates H and I, and when plate K is in its extreme position at the left the upper ends of its slots k, k', and k² will be coincident with the upper ends of the slots of the guide-plates H and I, as shown in Fig. 3. The slots of plates H and I are slanted or inclined from the top until they reach a short distance from the bottom, when they become vertical. They are variously inclined to operate the sliding plate K to the position desired. These plates H and I are of course rigid, and two are employed for the purpose of more evenly and accurately guiding the sliding plate K. At the front of the plate I is a shield J, which is fastened upon the horizontal ledge of the plate I by means of screws j.j.

Above the plates K, I, and H are the handle F' and the projecting pin F², the latter being adapted to be forced down into the slots of plates H and I and also the slots of slide-plate K whenever the handle F' is manipulated for this purpose. It will be observed that the slots k, k', and k² vary as to their inclination. Hence when the pin F² engages slot k and pursues a vertical downward movement, guided by the slots in the plates H and I, the result will be to shift the plate K to a greater distance endwise than when the pin F² engages the slots k' or k, which are of less inclination than k, and thus the extent of the endwise movement of plate K will depend upon which of its slots is engaged by the pin F². The parts are so arranged and the machine is de-

signed to be so operated that when the pin F² is engaged with the slot k of plate K the punch d will penetrate the commissary card, severing or obliterating a certain number, 55 which number will be indicated by the registering mechanism, and when the pin F² is engaged with slot k' a different number will be cut or punched from the card, which number will be indicated by the register, and so a different number with respect to slot k². Of course the plate K may have any desired number of slots and the register be constructed accordingly with index capabilities.

Numerous changes may be made in the various mechanical parts of my invention without departing from the same.

Having thus described my invention, what I claim as new, and desire to secure by Letters Patent, is—

1. In an automatic check-punch, the combination with a punching-die, of an actuating-cam provided with a movable handle, a slotted slide-plate, slotted guide-plates therefor, said plates being engageable by a pin on the handle, and registering mechanism actuated by the slide-plate, substantially as described.

2. In a check-punch, the combination with a spring-provided punching device, of an actuating-cam, a movable handle for said cam, a slotted slide-plate, slotted guide-plates therefor, a register operated by the slide-plate, and a pin on the movable handle that engages the slotted plates.

3. In a check-punch, the combination with a spring-provided punching device, of an actuating-cam, a movable handle pivoted thereto and having a forwardly-projecting pin, a slide-plate having diversely-inclined slots, 90 slotted guide-plates for the slide-plate, a register, one of whose ratchet-wheels is engaged by a pivotal pawl on the slide-plate, and a spring-pin in the end of said slide-plate for returning the same to position, substantially 95 as described.

In testimony whereof I affix my signature in presence of two witnesses.

GEORGE M. BRADT.
